INK RIBBON MECHANISM FOR TYPEWRITERS AND LIKE MACHINES

Joseph Patrick O'Halloran, London, England, assignor to Okopa Carbon Paper Eliminator Limited, London, England

Application March 24, 1937, Serial No. 132,867.
Renewed January 17, 1939. In Great Britain
January 2, 1937

6 Claims. (Cl. 197—153)

This invention relates to attachments for typewriters, calculating machines and the like of the kind in which an auxiliary ink ribbon is employed in addition to the main ink ribbon, for the purpose of making an original and one or more copies without the use of carbon paper.

It is important to provide means whereby the auxiliary ribbon can be kept at a sufficient tension to prevent it from sagging and soiling the paper, and also to permit the sheets of paper to run into their proper positions in relation to the ribbons, and the object of the invention is to provide a tensioning device for this purpose.

According to the invention the ends of the auxiliary ribbon are wound on spools, one of which is provided with means for winding the ribbon on to it from the other spool at the conclusion of the typing of a line, and the other of which is provided with a spring which opposes the winding operation aforesaid. This spring serves to hold the ribbon at the proper tension and affords a means for rapidly rewinding the ribbon when it is necessary to do so. Preferably the first-mentioned spool is driven by a pawl and ratchet mechanism under the control of the line-spacing mechanism.

One form of ribbon tensioning device for the auxiliary ribbon will now be described in detail with reference to the accompanying drawings.

It is to be understood, however, that I do not limit my invention to the details of construction illustrated which are given by way of example only. In the drawings:—

Fig. 1 is a perspective view showing the device fitted to a typewriter of conventional construction,

Fig. 2 is a section through the platen of the typewriter showing how the paper sheets are fed into proper position relatively to the main and auxiliary ribbons,

Fig. 3 is a perspective view of the separating pan,

Fig. 4 is a plan view of the drum for the left hand auxiliary ribbon spool,

Fig. 5 is a view looking in the direction of the arrow A in Fig. 4,

Fig. 6 is a plan view of the drum for supporting the right hand spool,

Fig. 7 is a section on the line VII—VII in Fig. 6 showing the spring unwound, and

Fig. 8 is a section on the line VIII—VIII in Fig. 7, but with the spring fully wound.

Like reference numerals indicate like parts throughout the drawings.

The typewriter may be of any standard type,

and comprises a fixed body portion 10 on which is supported the usual traveling carriage 11 carrying the platen 12. The machine includes the usual typewriter keys 13, type bars 14, spools 15 for the main ribbon 16, and ribbon vibrator 17. One of the spools 15 is driven by a pawl and ratchet mechanism (not shown) in known manner to present a fresh portion of the main ribbon at the printing position after the typing of each character.

In order to equip the machine with an auxiliary ribbon and thereby dispense with the use of carbon paper, it is fitted with two additional spools 18, 19 for the auxiliary ribbon 20, which are attached respectively to the carriage and to the body of the machine, with guides 22, 23 for the auxiliary ribbon, and with a paper separating pan 24. The guides 22, 23 are fixed by screws 25 to the carriage, and the guide 22 carries a bracket 26 for supporting the spool 18. The spool 19 is supported by a bracket 27 attached to the side of the body portion of the machine by screws 28 (see Fig. 7). The top bar 29 of the pan 24 is attached to the carriage by screws 30, and carries four downwardly projecting shield members 31 which extend around the platen 12 inside the paper guide 32 (see Fig. 2) and serve to feed the sheets of paper to correct position. The upper end of each shield member 31 is thinned to a fine edge at 33, these edges being located just behind the lower edge of the auxiliary ribbon 20 when the parts are assembled.

In order to make two copies three sheets of paper a, b, c are inserted into the machine at the top as indicated in Fig. 2, and caused to travel around to the printing line by turning the platen by means of the knob 34. As will be seen the pan 24 diverts the front two sheets into position between the two ribbons, while the rear sheet a is brought into position behind the auxiliary ribbon 20. An original imprint of the matter typed will then be made on the front surfaces of the sheets a, c and on the rear surface of the sheet b, which should be of thin paper so that the matter typed on it can be read from the front. If extra copies are required these may be made with carbon paper between the sheet a and the platen in the ordinary way. The transparent sheet b can be omitted if desired but in this case it is desirable to introduce a shield of Celluloid or other convenient material behind the sheet a to prevent its rear surface from receiving an imprint from the auxiliary ribbon.

The auxiliary ribbon is kept under a tension sufficient to prevent it from sagging and soiling

the paper solely by means of a spring 35 associated with the spool 19, no guide extending along the printing line being necessary. The spool 19 carries a downwardly projecting pin 36 adapted to engage a hole 37 in a plate 38 fixed to a spindle 39 rotatably mounted in the bracket 27. The spool 19 is held in position on the spindle 39 by a detachable screw cap 40. The lower end of the spindle 39 passes through a drum 41 containing the spring 35 and having a projecting lug 42 which coacts with the bracket 27 to hold the drum against anti-clockwise rotation as seen from above, and thereby permits the spring to be wound up on anti-clockwise rotation of the spindle 19, as the auxiliary ribbon 20 is drawn over to the other spool 18.

Inside the drum 41 is a sleeve 43 rotatably mounted on the spindle 39 and having a tooth 44 which co-operates with a pin 45 on the spindle. The sleeve 43 is attached to the inner end of the spring 35 by means of the screw 46. The outer end of the spring 35 is attached by a rivet 47 to a split ring 48 sprung within the drum 41.

As the auxiliary ribbon is unwound from the spool 19, the spindle 39 will be turned anti-clockwise with the result that the pin 45 will turn the sleeve 43 anticlockwise, thus winding up the spring 35. The attachment of the outer end of the spring to the split ring 48 instead of to the drum itself permits of a certain amount of slip between the spring and the spool box, and enables the spring to deal with a very large length of ribbon without danger of breaking.

A certain length of the auxiliary ribbon is wound over from the spool 19 to the spool 18 on actuation of the line space lever 56 at the conclusion of the typing of a line. This is done as follows:—

The spool 18 is loosely mounted on a spindle 40 50 journaled in a U-shaped bracket 49 fixed to the bracket 26. To the bracket 49 is attached an angle member 51, the upright limb of which is connected to a U-shaped frame 52, in which is journaled a vertical spindle 53. To the spindle 45 53 is fixed a crank 54, pivoted to a link 55 by which it is connected to the line space lever 56. To the lower end of the spindle 53 is fixed a crank 57 connected by a link 58 to a U-shaped lever 59 journaled on the spindle 50. On the lever 59 is 50 pivoted a pawl 60 which co-operates with a ratchet 61 fixed to the spindle 50, and co-operating with a check pawl 67.

On actuation of the line space lever therefore, movement is communicated through the members 55 55, 54, 53, 57, 58, 59, 69 to the ratchet wheel 61 to cause it to rotate clockwise as seen from above. A pin 62 on the lower surface of the spool 18 normally engages with one of three holes 63 in a plate 66 fixed to the spindle 50, the spool being held 60 with its pin so engaged by the screw cap 64. Consequently the spool 18 partakes of the clockwise movement of the spindle, thereby unwinding ribbon from the spool 19 against the action of the spring 35, the spring continually holding the ribbon taut. When it is desired to return the ribbon to the spool 19, the screw cap 64 is slackened, whereupon a leaf spring 65 lifts the spool 18 until its pin 62 is clear of the hole in the plate 66, thus uncoupling it from its pawl and ratchet 65 drive and enabling it to rotate counter-clockwise, with the result that the ribbon is wound back on to the spool 19 by the spring 35.

In typewriters or the like operating with an auxiliary inking ribbon, it has been the practice to 75 fit round the platen a curved sheet of metal or

other suitable material such as 24 and known as the "pan", which serves to separate the sheets to be typed upon by the main and auxiliary ribbons. It has so far been the practice to provide on the front face of the pan, in front of the platen, a 5 guide or ledge for supporting the auxiliary ribbon, with the result that when capitals are being typed, an impression of the small letter carried on the type-bar beneath the capital is received, through the thickened portion of the pan below 10 the ledge, on the paper behind the pan.

By the provision of the tensioning device for the auxiliary ribbon according to the invention, I am able to overcome this difficulty, because since the pan no longer has to support the auxiliary 15 ribbon, its front portion can be thinned down at 33 to an extent such that while still serving to separate the sheets of paper, there is no longer any danger of it being struck by characters on the type-bars below those which are printing. 20

A further important advantage of the chamfering of the edge of the pan at 33 is that this leaves room for the auxiliary ribbon to travel past the paper without the paper being bulged by the pan into contact with the ribbon. It also obviates any 25 risk of the auxiliary ribbon being lifted with the paper, when the platen is turned on operation of the line spacing lever.

The auxiliary ribbon tensioning device according to the invention can of course be employed in conjunction with calculating, accounting or like machines in addition to typewriters, and the term typewriting machine used in the appended claims is to be understood as including such other machines in addition to typewriters. 30

What I claim as my invention and desire to 35 secure by Letters Patent is:—

1. The combination with an auxiliary ribbon spool for attachment to a typewriting machine of a spindle, means for detachably coupling the 40 spool to the spindle for rotation therewith, a coiled spring operatively connected at one end to the spindle, a drum surrounding the spring, and a split ring sprung into the interior of said drum and connected to the other end of said spring. 45

2. The combination as claimed in claim 1, in which the drum is rotatably mounted on the spindle, the drum having a lug co-operating with a fixed stop to restrict rotational movement of the drum on movement of the spindle in the 50 direction to wind up the spring.

3. In a typewriting machine comprising a fixed body portion, type bars mounted thereon, a paper carriage slidable on said body portion, a platen rotatably mounted on said carriage and a line 55 space lever, the combination of a pair of ribbon spools, one at least of which is mounted on the carriage, driving means for effecting, on actuation of the line space lever, intermittent rotation of said carriage-carried spool to wind ribbon thereon 60 from the other spool, a spring associated with said other spool for holding said ribbon in tension, and release means for uncoupling the first-mentioned spool from its driving means to permit of uninterrupted reverse feed of the ribbon by the 65 spring.

4. In a typewriting machine comprising a fixed body portion, type bars mounted thereon, a paper carriage slidable on said body portion, a platen rotatably mounted on said carriage and a line 70 space lever, the combination of a pair of ribbon spools, one of which is mounted on the carriage and the other of which is mounted on the body portion, driving means for effecting, on actuation of the line space lever, intermittent rotation of 75

5 said carriage-carried spool to wind ribbon thereon from the other spool, a spring associated with said other spool for holding said ribbon in tension, and release means for uncoupling the first-mentioned spool from its driving means to permit of uninterrupted reverse feed of the ribbon by the spring.

10 5. The combination, with an auxiliary ribbon spool for attachment to a typewriting machine, of a driving spindle for the spool, means constituted by a screw cap fitting on to the end of the spindle, for coupling the spool to the spindle for rotation therewith, driving means for imparting intermittent rotational movement to the spindle, and release means for uncoupling the spool from the spindle to permit the spool to ro-

15 tate freely on the spindle, said release means comprising a spring which is held inoperative when the screw cap is in position, but is freed to uncouple the spool from the spindle on slackening of the screw cap.

6. The combination with an auxiliary ribbon spool for attachment to a typewriting machine, of a driving spindle for the spool, a spring acting to uncouple the spool from the driving spindle, and a coupling device which is operable to render 10 the spring ineffective and couple the spool to the spindle for rotation therewith, and which is movable to a release position, in which the spring is freed to uncouple the spool from the spindle.
